E. W. Robinson

UNITED STATES PATENT OFFICE.

EARL W. ROBINSON, OF MINNEAPOLIS, MINNESOTA.

SCAFFOLD HOIST.

Application filed August 16, 1923. Serial No. 657,767.

To all whom it may concern:

Be it known that I, EARL W. ROBINSON, a citizen of the United States, residing at Minneapolis, in the county of Hennepin and State of Minnesota, have invented certain new and useful Improvements in Scaffold Hoists, of which the following is a specification.

This invention relates to scaffold hoists and the main object is to provide a practical, efficient and easily operated means for raising and lowering scaffold platforms such as are commonly used by painters, masons, carpenters and other builders who work on the sides of buildings, boats, etc. Further and more specific objects will be disclosed in the course of the following specification, the invention being illustrated in the accompanying drawing, wherein:

Fig. 1 is a perspective view of one end of a hanging platform showing the application of my invention.

Fig. 2 is an elevation of the hoisting device shown in Fig. 1, on an enlarged scale and with portions broken away.

Fig. 3 is a vertical section on the line 3—3 in Fig. 2.

Fig. 4 is an enlarged sectional detail on the line 4—4 in Fig. 2.

Referring to the drawing more specifically and by reference characters 5 designates a main housing, having a hook 6 from which one end of a platform 7 is suspended by a cable 8. Only one hoisting device is shown, but it will, of course, be understood that another will be required at the other end of the platform or scaffold to be raised or lowered.

The device is suspended from the roof or a window, or other suitable support, in the usual manner, by a long cable 9, which extends down into the housing 5 and is wound upon a drum 10. The drum is fixed on a shaft 11, which is journaled in the housing 5, and carries a worm gear 12 meshing with a worm 13 on a shaft 14. The worm shaft is provided with a bearing member 15, journaled in the housing. The pin 16 is detachably secured in the housing, and normally retains the member 15 in rotatable but non-slidable position in the housing by engaging in a peripheral groove 17 therein. A hand crank 18 is secured on the end of the shaft 14.

As the weight of the scaffold is always on the cable 9 it will be understood that the worm gear 12 will always act against the worm 13 in the direction indicated by the arrow A, and that therefore there can be no tendency for the worm or its shaft 14 to work out of the housing in the direction of the handle 18. If, however, it is desired to unwind a long stretch of the cable 9, as when the scaffold is on the ground and the cable is to be pulled up for engagement with its hanging support, then the pin 16 is extracted and the handle 18 is turned to the left, in a counter-clockwise direction, thus screwing the worm 13 off of the gear 12. This will leave the drum 10 free to rotate so that the cable can be freely and quickly pulled out of the housing to the desired extent, at which time the worm is again engaged and the pin 16 is re-inserted.

It will thus be readily understood that, under normal circumstances, the drum will be locked in any position to which it is turned, by the worm 13; and can be turned only by the crank 18, to adjust the length of the cable 9 and the height of the scaffold platform 7.

It is further understood that suitable modifications may be made in the general design and structural details of the invention, as herein disclosed, provided, however, that such modifications come within the spirit and scope of the appended claim. Having now, therefore, fully shown and described my invention, what I claim to be new and desire to protect by United States Letters Patent is:

In a scaffold hoist, the combination with a body member, of a drum journaled therein, a cable having its lower end wound upon the drum to carry the weight of the hoist and scaffold, a worm gear for turning the drum, a worm shaft having a worm at one end meshing with said gear, and a crank at the other end to turn the shaft, means for slidably journaling the shaft so that said worm may be moved longitudinally into or out of engagement with the worm gear, a bearing member on the shaft having a peripheral groove, and a pin removably secured in the body member for engagement in said groove.

In testimony whereof I affix my signature.
EARL W. ROBINSON.
